UNITED STATES PATENT OFFICE

2,585,061

FABRIC STRIP AND HOLDER THEREFOR

Alfred B. Wester, Jr., Woodbury, N. J.

Application September 10, 1948, Serial No. 48,587

12 Claims. (Cl. 15—231)

1

This invention relates to new and useful improvements in cleaning devices and the primary object of the present invention is to provide a novel and improved sanitary cleaner for teeth and which is applicable for polishing shoes, silverware, fibrous material and the like in a convenient and highly satisfactory manner.

Another important object of the present invention is to provide a cleaner including a support having a pair of spaced walls, a strip of cleaning material trained over one of the walls and embodying novel and improved means for clamping the material to the other of said walls and relatively tight against the first mentioned wall.

Yet another object of the present invention is to provide a tooth cleaner including a support about which there is trained a strip of flexible cleaning material, means for clamping the material to the support when the same is in use, and novel and improved means for releasing said clamping means so that a new and clean portion of the material will be in position for use and means whereby the used portion of the strip may be removed.

A further object of the present invention is to provide a cleaner of the aforementioned character that is small and compact in structure and which includes in its construction a group of separable elements which are quickly and readily assembled or disassembled facilitating a cleaning of the same in a convenient manner.

A still further aim of the present invention is to provide a tooth cleaner that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of one embodiment of the present invention;

Figure 2 is a group perspective view of Figure 1 showing the clamping member separated from the support, the cleaning material removed therefrom, and with parts of the housing closure broken away;

Figure 3 is a longitudinal vertical sectional view taken substantially on the plane of section line 3—3 of Figure 1, but showing the locking member in clamped position; and,

2

Figure 4 is a transverse vertical sectional view taken substantially on the plane of section line 4—4 of Figure 3.

Referring now to the drawings in detail, wherefore in for the purpose of illustration, there is disclosed a preferred embodiment of the present invention, the numeral 10 represents a hollow substantially annular housing forming a hand grip and including an outwardly projecting hollow extension 12 that terminates in a support 14.

One side of the housing 10 is provided with an entrance opening 16 and an arcuate recess 18 is provided in the outer periphery of the housing 10 adjacent the opening 16.

15 A closure 20 is provided with an annular recess 22 in its inner face that receives the outer edge 24 of the housing 10, at the open side thereof, and the closure 20 is provided with an arcuate flanged portion 26 that is slidably and frictionally 20 fitted in the recess 18 for retaining the closure 20 in position to the housing 10 in order to close the opening 16.

An annular member or ring 28 is fixed to the closed side of the housing 10 and is spaced from 25 the inner annular surface of the housing 10. This member 28 forms a support about which there is trained a length or strip of flexible cleaning material or cloth 30.

The outer portion of the extension 12 or outer 30 extremity of the housing 10 is provided with an opening 32 that is positioned between the upper wall of the extension 12 and the lower wall 34 of the support 14.

Integrally formed with the side wall 36 of 35 the support 14 is a substantially rectangular upper wall or bearing plate 38 that is spaced from the lower wall 34 of the support 14 and which opposes a central recess or notch 40 formed in the lower wall 34.

40 The numeral 42 represents the clamping mechanism that is used in conjunction with the present invention generally and which includes a substantially rectangular pressure plate 44 that is loosely positioned between the walls 34 and 38.

45 Spaced parallel end blocks 46 and 48 are integrally formed with the upper surface of the plate 44 and include outwardly inclined outer surfaces 50 and 52, and transverse slots 54 and 56 are provided in the plate 44 adjacent the blocks 46 and 48.

The upper upstanding end portions of the bottom wall are recessed on both longitudinal sides and lugs or pivot pins 58 project outwardly from these recesses and engage notches 60 provided 55 in the free ends of a plurality of links 62 which

are pivotally secured to the ends of the blocks 46 and 48, for pivotal movement of the plate 44 relative to the lower or bottom wall 34.

Protuberances 64 projecting from the wall 34 are received in recesses 66 in the links 62 in order to lock the plate 44 clamped downwardly relative to the wall 34 as shown best in Figures 3 and 4, and with the inclined surface 50 of the block 46 bearing against the sloping outer edge 68 of the extension 12.

The upper outer edge 70 of the block 48 is sharpened to provide a means for tearing the material 30.

In practical use of the present invention, thus illustrated in Figures 1-4 inclusive, the free end portion 12 of the material 30 extends through the opening 54 in the plate 44, over the bumper plate 38, downwardly through the opening 56 in the plate 44, and upwardly about the block 48, as shown in Figures 1 and 3, the blocks 46 and 48 being raised to their dotted line position as shown in Figure 3. As the plate 44 is forced downwardly, the block 46 seals the opening 32 and the plate 44 clamps the material 30 between the plate 44 and the bottom wall 34, and the recesses 66 receive the protuberances 64 to lock the plate in this position.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A tooth cleaner comprising a hollow housing forming a hand grip, an elongated support projecting outwardly from said housing, said housing having an opening therein communicating with said support, said support including upper and lower walls, a length of flexible cleaning material in said housing having a free end portion extending through the opening in said housing and trained over the upper wall of said support and means for clamping said material against the lower wall of said support and including means for sealing the opening in said housing, said clamping means including a pressure plate, means pivotally securing said pressure plate to said support, and means for locking said pressure plate in position for clamping said material against the lower wall of said support and for closing the opening in said housing.

2. The combination of claim 1 wherein said means pivotally securing said pressure plate to said support includes a plurality of links between said pressure plate and the lower wall of said support.

3. A tooth cleaner comprising a hollow housing forming a hand grip, an elongated support projecting outwardly from said housing, said housing having an opening therein communicating with said support, said support including upper and lower walls, a length of flexible cleaning material in said housing having a free end portion extending through the opening in said housing and trained over the upper wall of said support and means for clamping said material against the lower wall of said support and including means for sealing the opening in said housing, said clamping means including a pressure plate disposed between the upper and lower walls of said support, a plurality of links pivotally securing said pressure plate to the lower wall of said support, and means for locking said pressure

plate in a clamped position relative to the lower wall of said support.

4. The combination of claim 3 wherein said locking means includes protuberances projecting from said lower wall, and recesses provided in said links adapted to receive said protuberances.

5. A tooth cleaner comprising a housing, an elongated support projecting outwardly from the housing, said housing having an opening therein communicating with said support, said support including spaced upper and lower walls, lugs rising from the lower wall of said support and extending toward the upper wall of said support, a clamping plate interposed between said lugs and said upper wall, means pivotally securing the ends of said clamping plate to said lugs for swinging movement of said clamping plate toward and away from said lugs, a flexible cleaning material received in said housing and having a portion extending through the opening in said housing, said clamping plate having a pair of openings therein receiving the portion of said cleaning material, the portion of said cleaning material being trained over the upper wall of said support, and means for locking the clamping plate to the lugs for clamping the cleaning material against the lugs.

6. A fabric strip holder comprising an elongated support having spaced upper and lower stationary walls, an elongated clamping plate disposed between the upper and lower walls of said support, means pivotally securing the ends of said clamping plate to one of said walls for swinging movement of said clamping plate toward and away from said lower wall, and means engaging said pivot means for locking said clamping plate against said lower wall.

7. A fabric strip holder comprising an elongated support having spaced upper and lower stationary walls, an elongated clamping plate disposed between the upper and lower walls of said support, means pivotally securing the ends of said clamping plate to one of said walls for swinging movement of said clamping plate toward and away from said lower wall, and interlocking means between said one of said walls and said first named means for holding the clamping plate toward the lower wall and against swinging movement.

8. A strip holder comprising spaced first and second walls, an elongated plate received between said walls for lateral movement relative to both walls and having openings adjacent its ends for receiving a strip of cleaning material on said first wall, links pivotally securing the ends of said plate to said second wall for swinging movement of said plate toward and away from said second wall, and locking means between said links and said second wall for holding the plate against swinging movement and a cleaning strip clamped between said plate and said second wall.

9. The combination of claim 8 wherein said locking means includes protuberances on said second wall, said links having recesses for receiving said protuberances upon movement of said plate toward said second wall.

10. A strip holder comprising a support having spaced upper and lower walls, a clamping plate received between said upper and lower walls, said clamping plate having a pair of openings therein, a flexible strip of material on said upper wall and having ends extending through the openings in said clamping plate and disposed

between the clamping and the lower wall, means pivotally and removably securing said clamping plate to the lower wall for movement of the clamping plate toward and away from the lower wall, and means holding the clamping plate against swinging movement with the ends of the strip clamped between said clamping plate and the bottom wall.

11. A tooth cleaner comprising a hollow housing forming a hand grip, an elongated support projecting outwardly from said housing and including upper and lower stationary walls, said housing having an opening therein communicating with said support, said upper wall having a pair of spaced openings therein, a length of flexible material in said housing having a free end portion extending through the opening in said housing and the openings in said upper wall and being trained over the upper wall, a pressure plate within said support and disposed between said upper and lower walls, said pressure plate having enlarged end portions received in said openings in said upper wall, means pivotally securing both ends of said plate to said support

for selective movement of said plate toward and away from said lower wall and means for locking the pressure plate in a clamped position relative to the lower wall of said support, said pressure plate including an end closing the opening in the housing when the plate is locked in its clamped position.

12. The combination of claim 11 wherein one enlarged end portion of said plate is sharpened and constitutes a cutting edge.

ALFRED B. WESTER, JR.
